UNITED STATES PATENT OFFICE.

WILLIAM H. HAWS, OF JOHNSTOWN, PENNSYLVANIA, ASSIGNOR OF ONE-EIGHTH TO HERMAN WAGNER AND ONE-EIGHTH TO JONATHAN E. RAGER, BOTH OF JOHNSTOWN, PENNSYLVANIA.

METALLIC RAILWAY-TIE.

1,010,756.

Specification of Letters Patent.

Patented Dec. 5, 1911.

Application filed April 3, 1911. Serial No. 618,723.

To all whom it may concern:

Be it known that I, WILLIAM H. HAWS, a citizen of the United States, residing at Johnstown, in the county of Cambria and 5 State of Pennsylvania, have invented certain new and useful Improvements in Metallic Railway-Ties, of which the following is a specification.

The invention relates to improvements 10 in metallic railway ties.

The object of the present invention is to improve the construction of metallic railway ties, and to provide a simple, efficient and inexpensive railway tie of great strength and 15 durability, equipped with means for securely holding the rails and of effectually preventing the same from either spreading or moving inwardly out of the proper gage.

A further object of the invention is to 20 provide a metallic railway tie of this character, adapted to receive and support the adjacent ends of the rails, and capable of permitting a limited vertical vibration of the 25 ends of the rails to prevent the same from being crushed or otherwise injured by the wheels of trains.

With these and other objects in view, the invention consists in the construction and 30 novel combination of parts hereinafter fully described, illustrated in the accompanying drawings, and pointed out in the claims hereto appended; it being understood that various changes in the form, proportion, size and minor details of construction, with- 35 in the scope of the claims may be resorted to without departing from the spirit or sacrificing any of the advantages of the invention.

In the drawings:—Figure 1 is a side elevation of a metallic railway tie, constructed 40 in accordance with this invention, the rails being in section. Fig. 2 is an end elevation of the same. Fig. 3 is a longitudinal sectional view on the line 3—3 of Fig. 2. Fig. 4 is a transverse sectional view on the line 4—4 of Fig. 3. Fig. 5 is a transverse sectional view on the line 5—5 of Fig. 3. Fig. 6 is a transverse sectional view on the line 6—6 of Fig. 1. Fig. 7 is a detail perspective view of the adjustable rail clamping jaw. Fig. 8 is a detail perspective view of the rail supporting bar. Fig. 9 is a side elevation of one end of a metallic cross tie,

showing another form of slot for the adjustable rail clamping jaw.

55

Like numerals of reference designate corresponding parts in all the figures of the drawings.

In the accompanying drawings in which is illustrated the preferred embodiment of 60 the invention, 1 designates a metallic cross tie, constructed of suitable metal and approximately U-shaped in cross section and consisting of a horizontal bottom 2 and vertical sides 3, formed integral with the bottom 2. The cross tie is provided at each end with a rigid integral rail clamping jaw 4, extending across the metallic tie and projecting above the plane of the upper edges of the sides, and provided with inner vertical and inclined rail engaging faces or 65 edges 5 and 6, conforming to the configuration of and fitting against the web and base of the rails 7.

The rails 7 at each end of the cross tie are 70 supported upon transverse bars 8, constructed of suitable metal and arranged in recesses 9 of the sides 3 of the metallic cross tie and provided at their inner side edges with notches 10, receiving the inner side 75 edges 11 of the recesses 9, whereby the rail supporting bars are interlocked with the sides of the metallic cross tie. The inner side walls or edges of the recesses 9 are inclined, and the co-acting walls 12 of the 80 notches 10 are correspondingly inclined to produce a wedging action of the rail supporting bar in the said recesses 9. The rail supporting bar is provided at its upper face with a longitudinal recess or depression 13, 85 located beneath the ends of the rails and adapted to permit sufficient vertical vibration of the same to prevent the rails from being crushed by the wheels of trains, as would be the case were they seated upon a 90 solid supporting surface. The end portions of the bars 8 receive the rails at a sufficient distance from their terminals so as not to interfere with the vibrations of the ends of the rails.

100 The rails are securely held on the cross tie by means of an adjustable clamping jaw 14, operating between the sides of the cross tie and consisting of a transverse top 15, vertical sides 16, a horizontal bottom 17, 105 and an intermediate horizontal portion 18,

connecting the sides and receiving adjusting rods or bolts 19. The top 15 of the rail engaging jaw is provided with vertical and inclined edges or faces 20 and 21, conforming to the configuration of the web and bottom flanges of the rails and fitting against the same. The sides 16 of the adjustable clamping jaw 14 fit against the inner faces of the sides of the cross tie, and the bottom 17 is extended laterally beyond the sides to form laterally projecting lugs 22, which are interlocked with slots 23 of the sides of the cross tie. In Figs. 1 to 5 inclusive the slots 23 are approximately inverted T-shaped, and each consists of a central vertical entrance branch or portion 24 and horizontal portions, extending longitudinally of the cross tie in opposite directions from the entrance branch 24, and having inclined upper walls 25 at their terminal portions. The longitudinal slots extend to points beneath the rails, and the laterally extending lugs 22 have inclined upper faces 26, forming wedges and fitting against the inclined top walls 25, whereby when the clamping jaw is drawn toward the rail by the bolt 19, it will also be carried downwardly, whereby the rail will be tightly clamped against the fixed jaw and against the horizontal transverse supporting bar 8.

The bolts 19 pierce the intermediate portion 18 of the adjustable clamping jaw and have their heads arranged in counter-sunk openings 27 of the same. The outer ends 35 of the bolts 19 pierce a transverse end portion 28 of the cross tie and are threaded for the reception of nuts 29, which may be keyed or otherwise held against rotation. The cross bar 28 is preferably formed integral 40 with the sides of the cross tie, but it may consist of a separate bar or piece fitted in the recesses in the end edges of the cross tie.

The cross tie is equipped with a cap 30, consisting of a horizontal top plate and 45 depending longitudinal side flanges 31, formed integral with the top plate and fitted against the inner faces of the sides of the cross tie. The cap, which projects beyond the side flanges and rests upon the upper 50 edges of the sides of the cross tie, extends along the space between the adjustable clamping jaw and is interposed between the same and is adapted to prevent the jaws from becoming disengaged from the rails, 55 even should the bolts 19 become loose. The cap closes the top of the cross tie and the side flanges may extend down a sufficient distance to cover the slots 23.

Instead of employing the long T-shaped 60 slots, the cross tie may, as illustrated in Fig. 9, be equipped at each end with approximately L-shaped slots 32, consisting of vertical entrance portions and horizontal outwardly extending portions, having inclined upper walls 33 to coöperate with the

laterally extending lugs of the adjustable jaw.

Having thus fully described my invention, what I claim as new and desire to secure by Letters Patent, is:—

1. The combination of a cross tie provided with a fixed rail engaging jaw and having spaced sides provided with inclined slots, an adjustable clamping jaw operating within the cross tie and having portions 75 slidably engaged with the said inclined slots and arranged to be drawn downward by the same, and adjusting means for the adjustable clamping jaw.

2. The combination of a cross tie provided with a fixed rail engaging jaw and having spaced sides provided with inclined slots, an adjustable clamping jaw provided with integral portions having inclined faces 85 slidably engaging the inclined slots of the sides of the cross tie, and adjusting means connected with the adjustable clamping jaw.

3. The combination of a cross tie provided with a fixed rail engaging jaw and having spaced sides provided with slots 90 having inclined walls, an adjustable clamping jaw operating between the sides of the cross tie and provided with laterally projecting lugs extending into the slots and having inclined faces to engage with the 95 said inclined walls, and adjusting means for moving the adjustable clamping jaw along the slots.

4. The combination of a cross tie provided with a fixed rail engaging jaw and 100 having spaced sides provided with opposite longitudinal slots, said sides being also provided with entrance or branch slots extending from the upper edges of the sides to the said longitudinal slots, an adjustable 105 clamping jaw fitted between the sides of the cross tie and provided with laterally projecting lugs arranged in the said slots, whereby the adjustable jaw is interlocked with the cross tie, and adjusting means for the 110 adjustable clamping jaw.

5. The combination of a cross tie having spaced sides provided with longitudinal slots, said cross tie being also provided with a fixed rail engaging jaw and having a cross piece located at the end of the cross tie, an adjustable clamping jaw operating between the sides of the cross tie and provided with projecting portions extending into the 115 said slots and interlocking the adjustable jaw with the cross tie, and a longitudinal bolt 120 connected with the adjustable clamping jaw and with the said cross piece.

6. The combination of a cross tie having spaced sides and provided with a fixed rail 125 engaging jaw, an adjustable clamping jaw composed of a top portion, vertical sides fitted against the inner faces of the sides of the cross tie, and bottom and intermediate portions connecting the sides of the adjustable 130

jaw, the bottom portion being slidably interlocked with the cross tie, and adjusting means connected with the said upper portion.

- 5 7. The combination of a cross tie having spaced sides provided with recesses having inclined walls, a transverse rail supporting bar extending across the tie and provided with notches having inclined walls to fit the
- 10 walls of the said recesses, whereby the said supporting bar is interlocked with the sides of the cross tie and wedged in the recesses thereof, and rail clamping means mounted on the cross tie.
- 15 8. The combination of a cross tie having spaced sides and provided at its ends with fixed rail engaging jaws, adjustable clamp-

ing jaws operating between the sides of the cross tie and co-acting with the fixed jaws to secure the rails to the cross tie, and a cap 20 fitted on the cross tie and extending along the same from one adjustable jaw to the other and adapted to prevent the same from becoming disengaged from the rails, said cap consisting of a plate supported upon the 25 upper edges of the sides of the cross tie and having depending flanges fitted against the inner faces of the said sides.

In testimony whereof I affix my signature in presence of two witnesses.

WILLIAM H. HAWS.
